WATER HEATER

Filed June 14, 1928

Fig. 1.

UNITED STATES PATENT OFFICE

WILLIAM YAEGER, OF BUFFALO, NEW YORK

WATER HEATER

Application filed June 14, 1928. Serial No. 285,446.

My invention relates to improvements in water heaters, and has more particular reference to the embodiment of means for cleaning the interior of the heater.

5 The invention is particularly adapted for use in connection with a coil-heater in which a chamber enclosing a water-coil is provided, and which heater is connected with a steam or other boiler, preferably the former, and 10 provision made for introducing steam from the boiler into the heater for freeing the coil and surrounding parts of the heater of sediment, incrustations, or other adhering matter.

15 The primary object of my invention is to provide means for effectively cleaning the interior of a water heater.

Another object of my invention is the provision of means for freeing sediment, 20 crustations, or other adhering matter from the interior coil and confining wall of a water heater.

Other objects of my invention are the provision of a water heater with a source for 25 water and a source for a cleansing agent; combined with means for heating the water supplied to the heater.

With the above and other objects in view, the invention consists in the novel features 30 of construction and arrangement and combination of parts to be hereinafter described and more particularly pointed out in the subjoined claims.

In the drawings:—

35 Fig. 1 is a sectional elevation of a steam boiler or the like and a source of water-supply illustrated in combination with my improved water heater, and the means for 40 cleansing the same.

Fig. 2 is a vertical longitudinal section through the water heater.

Fig. 3 is a transverse section taken on line 3—3, Fig. 2.

45 Fig. 4 is a vertical section through the

upper part of the water heater, showing my invention in modified form.

Fig. 5 is a transverse section taken on line 5—5, Fig. 4, looking in the direction of the arrow crossing said line.

Reference being had to the drawings in detail, 6 designates a steam boiler, 7 a water reservoir for the storage of water, and 8 the water heater.

The water heater comprises a casing or chamber 9 of any suitable form, but preferably cylindrical and vertically elongated. Connecting a high point of the water space of the steam boiler with the casing or chamber 9, at or near its upper end, is a hot-water pipe 10 having a hand valve 11 therein for opening or closing the passage therethrough. Connecting the lower end of the casing or chamber 9 with a low point of the water space in the steam boiler 6 is a cooled-water pipe 12, in which is arranged a hand valve 13 by means of which the passage through said pipe may be opened or closed.

Provision is therefore made, by reason of the connection of the pipes 10 and 12, to feed 70 hot water from the steam boiler to the upper end of the chamber 9 and to allow said water, when cooled in a manner to appear hereinafter, to be returned to the boiler at a low point through the pipe 12. A continual circulation of hot water through the chamber 9 is therefore provided.

A pipe 14 connects the water reservoir 7 at a low point thereof with a fitting 15 secured 80 radially into the chamber 9 at a low point, and this fitting has connected thereto within the chamber 9 the lower end of a water coil 16 disposed vertically within said chamber and having its axis coaxial therewith. 85 The upper end of this coil is connected to a fitting 17 radially secured within the chamber 9 at its upper end and a water pipe 18 connects the fitting 17 with the water reservoir 7 at a high point thereof.

Water is supplied to the water reservoir 7 by a pipe (not shown), in any suitable manner, and the water within the reservoir is fed to the lower end of the coil 16 by means 5 of the pipe 14. The water within the coil is heated by the hot water circulating through the chamber 9 and pipes 10 and 12, and as the water in the coil becomes heated it ascends and passes into the water reservoir 7 through 10 pipe 18. A hot-water supply pipe 19 is connected to pipe 18, and through a portion of the latter this pipe 19 has connection with the reservoir 7.

All of these parts are now commonly in 15 use, but the heater differs from the commonly known water heater of this type in that its head 20 is provided with an axial screw-threaded opening 21 in which is arranged an internally screw-threaded bushing or fitting 20 22. Into the upper portion of this bushing or fitting a pipe 23 is screw-threaded which leads to the top of the steam boiler and has a water pipe 24 connected therewith.

The water pipe 24 is provided with a hand 25 valve 25 and the pipe 23 is also provided with a hand valve 26. The head 20 is fastened to the upper end of the chamber by means of screws (not shown), or otherwise, and is rendered water tight by a gasket 27 clamped 30 between the two.

Threaded into the lower portion of the bushing or fitting 22 and extending into the chamber 9 is a nipple 28, and fastened to the inwardly-projecting portion of this nipple is 35 a cleaning tube 29 which may be provided with one or more longitudinally-disposed slots 30, transverse slots 31, and small openings 32; or, if desired, any type of opening or openings may be provided in this tube for 40 the passage therethrough of steam delivered thereto from the dome of the steam boiler through the medium of the pipe 23. This cleaning tube is readily removable from the chamber and as readily insertable thereinto; it being simply necessary to disconnect the pipe 23 from the bushing or fitting 22 and then disconnect the fitting from the head 20, whereupon the cleaning tube 29 can be withdrawn through the opening 21 in the head, 45 thus making it unnecessary to remove the head from the chamber. In water heaters of this type the head is made solid and must be removed in order to gain access to the 50 interior of the heater.

In applying my invention to heaters now in use, it is my intention to substitute the head shown and described for the solid head generally used, as access to the interior of the chamber will not be necessary since the cleansing 55 operation can be effected automatically by opening up the valves 25 and 26, or either of them.

Connected to the pipe 12 is an outlet or 60 flushing pipe 33 which may be led to a sewer,

and in this outlet or flushing pipe is a hand valve 34.

When cleaning the interior of the water heater, and especially the coil, the valves 11 and 13 in the water circulating pipes connecting the water heater with the boiler, are closed. The valve 26 in the steam supply pipe is opened so as to allow steam to enter the cleaning tube 29, which is axially disposed within the water coil 16. The steam issues through the slots or openings, as the case may be, in this cleaning tube and attacks the water sediment, incrustations, or other matter adhering to the coils, and also the walls of the chamber 9. After a quantity of steam has been admitted to the chamber 9, the valve 34 may be opened, thus allowing the steam to pass with any loosened matter to the sewer.

If desired, the interior of the chamber may be flushed out, after closing the steam valve 26, with water delivered to the cleaning tube 29 through the pipe 24 and a part of the steam pipe 23 beneath this valve 26; thus the water thoroughly washes the interior of the chamber without in any manner requiring disconnection of parts. A thorough cleansing of the interior of the chamber can therefore be effected at regular intervals in a most convenient manner.

In the construction shown in Figs. 3 and 4, the head or cover of the casing is of somewhat modified form, and in these figures this head or cover is shown hollow so as to provide a chamber 35 having an inwardly-convexed inner or lower wall 36 provided with numerous perforations 37. The steam pipe 23 is directed into an axial opening 38 formed in the outer wall of this chambered head or cover, and a nipple 39 is threaded into the inner perforated wall; this nipple having the cleaning tube 29 threaded thereonto. When using this construction, steam is admitted through the pipe 23 and enters the chambered head or cover; part of the steam escaping through the perforations in said head or cover and being directed downwardly onto the side walls of the casing and onto the water coil, and the remainder of the steam being directed into the cleaning tube so as to escape through the numerous openings formed therein and attack the surface of the water coil from a central point.

Having thus described my invention, what I claim is:

1. The combination with a steam boiler and a source of water supply, of a water-heater having a removable top wall and conduit connection with the water in said steam boiler for circulating water through said heater, conduit connection between said heater and said source of water supply for circulating water to be heated through said heater, and a cleaning device within said heater fastened to said top wall and removable therewith and having connection with the top of said steam

boiler for delivering steam to the interior of said heater.

2. A water-heater, comprising a casing having a removable wall and a conduit for 5 the passage of water therethrough, the walls of said conduit being separated from the walls of the casing by a water space, said casing having an inlet and an outlet to provide for the passage of a heating agency 10 through said water space, and means extending into the casing from said removable wall and from which a cleaning agent may be directed against the walls of said conduit to cleanse the same.

15 3. A water-heater, comprising a casing having a removable head, a hot-water inlet opening into said casing at a high point and a cooled-water outlet therefor at a low point, a water coil disposed within said casing and 20 spaced from the walls thereof, a water inlet pipe connected to said casing and having connection with one end of said coil, a water outlet pipe connected to said casing and having connection with the other end of said coil, and 25 a pipe removably dependent from said head and extending axially through said water coil, said pipe having openings therethrough for directing a cleansing agent against all portions in the length of said coil.

30 4. A water-heater, comprising a casing having a chambered head provided with perforations in the inner wall of said head directed downwardly towards the interior of said casing, said head having a pipe connected exteriorly thereto to direct a cleansing agent 35 into said chamber, said casing having also an inlet pipe for the admission of a heating agent thereinto and an outlet pipe for the escape of the heating agent therefrom, a 40 water coil arranged within said casing and spaced from the wall thereof, said water coil having connection at one end with a water inlet pipe and at its other end with a water outlet pipe, and a perforated tube extending 45 axially through said coil from the perforated wall of said chambered head.

5. A water-heater, comprising an elongated casing, a water coil disposed within said casing, said casing having conduit connection with a source for a heating agency to 60 permit the passage of the heating agent through said casing, a water inlet pipe connected to one end of said coil, a water outlet pipe connected to the other end of said coil, and means for directing a cleansing agent 65 downwardly onto said coil and radially against said coil from the interior thereof.

6. A water heater, comprising a casing having a chambered head provided with perforations in the inner wall of said head directed 70 downwardly toward the interior of said casing, said head having a pipe connected exteriorly thereto to direct a cleansing agent into the chamber of said head, said 75 casing having also an inlet pipe for the admis-

sion of a heating agent thereinto and an outlet pipe for the escape of the heating agent therefrom, a water coil arranged within said casing and spaced from the wall thereof, said water coil having connection at one end with 70 the water inlet pipe and at its other end with the water outlet pipe and being adapted to have the cleansing agent directed thereagainst from the perforations in the inner wall of said head. 75

In testimony whereof, I affix my signature.
WILLIAM YAEGER.
